UNITED STATES PATENT OFFICE.

GEORGE S. GALLAGHER, OF NEW YORK, N. Y., ASSIGNOR OF ONE-HALF TO HENRY GALLAGHER AND ONE-HALF TO EMMA G. GALLAGHER, OF NEW YORK, N. Y.

STEAM-BOILER FURNACE.

1,084,853.

Specification of Letters Patent.

Patented Jan. 20, 1914.

Application filed August 22, 1912. Serial No. 716,356.

To all whom it may concern:

Be it known that I, GEORGE S. GALLAGHER, a citizen of the United States, residing in the borough of Manhattan, city, county, and State of New York, have invented a certain new and useful Improvement in Steam-Boiler Furnaces, of which the following is a specification.

My invention relates to improvements in steam boiler furnaces, and particularly to the devices associated with and in proximity to the coal doors, and the same is an improvement upon the devices shown and described in my application for Letters Patent, Serial No. 577,006, filed August 13, 1910.

In contra-distinction to the features of my said application, the object of my present invention is to facilitate and lessen the cost of manufacture of the parts of the jamb block and center pier block and their tile faces, to facilitate the placing of the tile faces and increase the circulation and discharge of the air in relation thereto.

In carrying out my invention, the cast metal frames or bodies of the jamb blocks and center pier are secured to the front furnace wall in about the same manner as in my aforesaid application, but said frames or bodies are perforated at right angles to the planes of their faces, and the backs of the tile faces and the edges are provided with a plurality of grooves. The surface grooves, when the tiles are in position, coincide with the perforations in the cast metal frames or bodies and the edge grooves provide air discharge apertures, whereby a circulation of air is established. The tile faces are held to the cast frames or bodies by bolts, all of which is hereinafter more particularly described.

In the drawing, Figure 1 is a sectional plan through a portion of the front of a steam boiler furnace at the coal door, illustrating the device of my invention. Fig. 2 is a perspective view of the center pier block or body, with the tile face or nosing in position in relation therewith. Fig. 3 is an elevation of the inner or back surface of this tile or nosing, and Fig. 4 is an elevation of the jamb block frames or bodies.

Similar letters and numerals of reference indicate the same parts in all the figures.

a represents the front metal plate of the furnace, which is provided with an opening constituting the entrance for coal, and *a*¹ is

the coal door closing said opening. *a*² represent holes in this front metal plate, providing for the entrance of air.

b is the base or dead plate of the coal door of the furnace, and beyond which are the ends of the grate bars *c* adjacent to the plate *b*.

In Fig. 1 of the drawing, I have only shown the center pier frame or body and one end jamb block, as this is apparently all that is necessary to illustrate the invention, the other end being similarly constructed.

d, at one end, represents one jamb block frame or body, which is of cast metal, provided with one or more lugs *d*¹ and advantageously with upper and lower or end webs *d*², which act as braces. As placed according to the illustration Fig. 1, it will be noticed that the right hand end of this jamb block is inserted in the wall of the furnace and the left hand end secured at the lug *d*¹ by bolts 2, hence the holes *a*² in the front wall *a* permit access of air between the front plate *a* and the jamb block *d*. This jamb block is made of several angles to fit the corner, and the same is perforated or provided with a plurality of holes 3, and also with bayonet slots 6 at about the center of each face for the purpose hereinafter described.

e represents the center pier or spacing frame or body of flattened U-configuration and provided with lugs *e*¹, adapted to come against the inner face of the front plate *a*, and these lugs are provided with threaded holes to receive other bolts 2, by which this center frame plate or body is secured to the front plate *a* of the furnace. This center pier is provided with a plurality of holes *e*² in the side portions and in the front portion, as shown in Figs. 1 and 2.

f represents the tile faces of the jamb block frames *d*. These are shaped to conform to the contour of the jamb block frames, and are provided with a plurality of horizontal grooves *f*¹ in their inner faces, and edge grooves *f*² which align with the grooves *f*¹, and the grooves *f*¹ coincide with the holes 3 of the jamb block frames, thus air that finds entrance between the jamb block frame, the front wall and the furnace wall, readily finds exit into the combustion chamber of the furnace through the holes 3 into the grooves *f*¹, and by the grooves *f*² into the combustion chamber, or in other words, there is a circulation of air estab-

lished in this way from outside of the furnace, or from below the grate door, as shown in my aforesaid patent, within the jamb block frames, and by the device of the present invention, therefrom into the combustion chamber.

I prefer to connect the tile faces *f* to the jamb block frame *d* by bolts, and for this purpose, preferably make recesses 4 in the faces of the tile members *f*, and holes through the same at these recesses, and employ bolts 5, which pass through the holes with the heads of the bolts in the recesses and with the stems of the bolts passing through the bayonet slots 6 in the jamb block frames, and the nuts of the bolts behind, or in other words, within the boundary of the jamb block frame. After the bolts are in place and are tightened up by any convenient device employed therefor, the recesses 4, in the tile faces *f*, are to be filled up with fire clay.

In connection with the center pier frame *e*, I have shown and prefer to employ a tile nosing *h* with a rounded end and flat back to rest against the projecting face of the center pier frame *e*, and in the device of my present invention, I have dispensed with the side tile faces of the center pier, which I have shown in my aforesaid application. The tile nosing *h* is grooved on the back, both horizontally and vertically, the horizontal grooves *h*² coinciding with the holes *e*² of the center pier frame, and the vertical grooves *h*¹ crossing the same and also corresponding with a vertical line of the holes *e*².

In order to connect the tile nosing *h* in position against the end of the center pier frame *e*, I prefer to employ an angular shaped bolt *i*, and to form a groove 7, in the upper surface of this tile nosing *h*, and in the upper edge of the center pier frame *e*, and at the end of the groove 7, in the tile nosing, a vertical hole, or in other words, a hole at right angles to the groove which receives the end of the bolt opposite to the threaded end which receives the nut. Fig. 1 shows the position of this bolt member, where the same lies in the groove 7 with the shorter end in the hole, in the tile nosing, and the stem of the bolt as extending forward and passing through the front plate *a* with the nut coming outside of the plate *a* where the same is accessible for the manipulation of the bolt. This bolt keeps the tile nosing in position, particularly in view of the fact that there can be no vertical movement as between the base plate *b* and the center of the usual arch plate or rigid member which supports the furnace wall. To replace the tile nosing, when damaged or burned out, with a new one, it is an exceedingly easy matter to remove the exposed nut of this bolt *i* and pull away the tile nosing

from the center pier frame with the bolt and in the inverse order to connect the parts in position.

The construction of the center pier frame *e* and the tile nosing *h* provides for a circulation of air and an escape of air into the combustion chamber, very similar to that explained in connection with the jamb block and the tile faces thereof, because the holes *e*² provide for an exit of air from within the center pier frame, not only directly but into the vertical grooves *h*¹ and horizontal grooves *h*² of the tile nosing and the escape of the air therefrom at the edges of the tile nosing, as shown in Fig. 2. This circulation of air not only affords the surplus air required in the combustion chamber for the proper combustion of the fuel but also assists in cooling the tile faces and the metal parts back of the same.

I have shown in Figs. 1, 2 and 3, and prefer to employ the vertically disposed angular rib 8 formed with and centrally of the center pier frame or spacing bar *e* projecting from the end thereof, and I provide the tile nosing with a vertically disposed center groove 9, as shown particularly in Fig. 3, by which it is adapted to set over this rib. By this device, the tile nosing may at once be accurately brought to position and any lateral motion prevented, because between the top and bottom plates of the furnace at the coal doors, this rib and groove, and the bolt *i*, the entire nosing is held most securely in position.

I claim as my invention:

1. In a steam boiler furnace, a hollow metal block, means formed therewith for connecting the same in position in the walls of a furnace, the walls of the block being provided with a plurality of apertures, and fire brick tiles forming faces for the sides of the block, the inner faces of the said fire brick tiles being provided with grooves so arranged as to lie in line with the perforations in the walls of the block, the said fire brick tiles being also provided with edge grooves communicating with the aforesaid face grooves so as to provide passages for the circulation of air from within the said block to the combustion chamber of the furnace.

2. In a steam boiler furnace, a hollow metal block, means formed therewith for connecting the same in position in the walls of a furnace, the walls of the block being provided with a plurality of apertures, fire brick tiles forming faces for the sides of the block, the inner faces of the said fire brick tiles being provided with grooves so arranged as to lie in line with the perforations in the walls of the block, the said fire brick tiles being also provided with edge grooves communicating with the aforesaid face grooves so as to provide passages for

the circulation of air from within the said block to the combustion chamber of the furnace, and means for removably securing the said fire brick tiles in position against the 5 faces of the said block.

3. In a steam boiler furnace, a spacing or center pier block adapted to be built in the front wall of the furnace between the coal doors, and means formed therewith for connecting the same to the front wall, said spacing or center pier block formed hollow and provided with a plurality of perforations on the sides and end, and a tile nosing adapted to fit against and project from the end of 10 the spacing or center pier block into the combustion chamber, and said tile nosing provided on its back face with a plurality of horizontally and vertically disposed grooves to come to the edges or margins of the said 15 tile nosing and co-incide with the perforations in the spacing or center pier block.

4. In a steam boiler furnace, a spacing or center pier block adapted to be built in the front wall of the furnace between the coal doors, and means formed therewith for connecting the same to the front wall, said spacing or center pier block formed hollow and provided with a plurality of perforations on the sides and end, and a tile nosing 20 adapted to fit against and project from the end of the spacing or center pier block into the combustion chamber, and said tile nosing provided on its back face with a plurality of horizontally and vertically disposed grooves to come to the edges or margins of the said 25 tile nosing and co-incide with the perforations in the spacing or center pier block.

block, and the upper edge of the forward portion of the center pier or spacing block notched, and the upper surface of the tiling 40 nosing grooved and perforated, and an angular shaped bolt adapted to be received in the said parts for connecting the tile nosing and the spacing block or center pier frame in 45 position.

5. In a steam boiler furnace, a spacing or center pier block adapted to be built in the front wall of the furnace between the coal doors, and means formed therewith for connecting the same to the front wall, said spacing or center pier block formed hollow and provided with a plurality of perforations on the sides and end, and a tile nosing adapted to fit against and project from the end of 50 the spacing or center pier block into the combustion chamber, and said tile nosing provided on its back face with a plurality of horizontally and vertically disposed grooves to come to the edges or margins of the said 55 tile nosing and co-incide with the perforations in the spacing or center pier block, and the forward portion of the said center pier or spacing block provided with a projecting rib, and the back portion of the tile nosing with a vertical groove fitting said rib, whereby the said tile nosing is brought at once to position with reference to the center pier or spacing block, and lateral motion is prevented.

Signed by me this 22nd day of July, 1912. 70
GEORGE S. GALLAGHER.
